UNITED STATES PATENT OFFICE.

PETER KAVANAGH, OF LIVERPOOL, ENGLAND.

TRAM-CAR.

No. 926,810.

Specification of Letters Patent.

Patented July 6, 1909.

Application filed June 5, 1908. Serial No. 436,853.

To all whom it may concern:

Be it known that I, PETER KAVANAGH, a subject of the King of Great Britain and Ireland, residing at 2 Egerton street, Liverpool, in the county of Lancaster, England, have invented a new and useful Improvement in Tram-Cars, of which the following is a specification.

This invention has for its object an improved type of double decked tramcar also applicable to vehicles for light railways and the like the main features of which are that there is a broad entrance at one end and a narrow exit at the other according to the direction in which the car is running and passengers will always alight on the safe side, thus doing away with the objectionable feature in ordinary cars of persons entering a car meeting or coming into collision with those leaving the car. Furthermore the stairs leading to the upper deck always directly face the incoming passengers and my car is so constructed that I am able to seat more passengers on the upper floor or deck than is possible with existing cars.

A further feature of the invention lies in the fact that the entrance doors are very wide and of sufficient breadth to allow a stream of people to enter and turn—to the left as illustrated—to gain access to the interior of the car, while another stream of people may at the same time pass to the stairs leading to the upper deck. The necessity for such a large opening for the exit doors does not exist as the passengers generally leave a car one by one or a few at any given stopping place and I so locate the stairs that a narrower but sufficient exit is provided and almost twice as wide an entrance. I thus conveniently dispose the stairway without constricting the entrance.

These and other improvements hereinafter described are carried out as follows reference being had to the accompanying drawings in which—

Figure 1 is a side elevation partly in section of my improved tramcar. Fig. 2 a plan one half being of the roof and the other a section through *g-g* Fig. 1. Fig. 3 a sectional plan through *x-x*. Fig. 4 an end elevation. Fig. 5 is fragmentary view partly in section of the left hand end of Fig. 1 and drawn to a larger scale. Fig. 6 is an enlarged view of the right hand end of Fig. 2, and showing some details hereinafter described. Fig. 7

is a reduced plan view in outline to more clearly indicate the direction taken by passengers entering or leaving the car. Fig. 8 is a plan view showing the means for opening and closing the entrance doors as hereinafter described. Fig. 9 is a sectional detail view of the stairs hereinafter described.

Like numerals refer to corresponding parts wherever they appear.

1 is the body of the car which is similar to existing ones, but the platforms 2 in this case are made a little longer than usual. The entrances to this car are provided with folding swing doors 3 which open inward as shown in Figs. 6 and 8, and opposite these on the other side of the car are narrower hinged doors 4 which serve for the exit of passengers.

Nearly opposite the entrances and at one side thereof are the stairs 5 leading to the top of the car and between the stairs and the ends 6 of the platforms are partitions 7 which completely cut off or isolate the driver, the remainder of the platform being open on all sides. These partitions are fitted with sliding glass doors 8 sliding windows 9 to allow of a current of air passing through the car, and hinged doors 10 leading to the space underneath the stairs which space can be utilized for storage.

The exit doors 4 which are of single width that is, sufficiently wide to allow one passenger at a time passing out, are preferably opened and closed from the driver's platform by means of handle 11 operating through rack 12 and pinion 13 a shaft 14 which by means of bevel wheels 13 turns a short upright spindle 16. This spindle which runs idle carries a chain wheel 17 and this by means of a chain 18 turns a sprocket 19 that is attached to the spindle 20 on which the door 4 is hung; 21, (see dotted lines Fig. 5) indicates additional gearing by means of which the door 4 can be opened or closed from the other end of the car if desired in obvious manner.

I provide a hinged seat 22 see Fig. 5 which is only intended to be dropped down for use when the exit door adjacent to it is closed, thus giving additional sitting accommodation at that end of the car that is at the rear for the time being. When said end becomes the front end owing to the change in direction of the travel of the car, and the exit door 4 at said end is required to be open the seat 22 is lifted back into its upright position and lies

in a recess provided for it in the partition 23 at the end of the inclosed portion of the lower deck of the car. The exit door also being opened lies over and covers the seat.

5 In some cases the seat 22 instead of being hinged so as to swing up out of the way when not required may slide into a recess made beneath the stairs at the opposite side.

10 Referring now more particularly to Figs. 6 and 8 the entrance doors 3 are of double width and the stairs 5 face them at one side. Although I use the convenient expressions single width and double width they are only to be taken as approximate and to indicate 15 that the exit doors are narrower than the entrance doors by the width of the satirway.

20 My invention also includes means whereby the entrance doors 3 may be opened and closed by the driver. These doors 3 are split vertically and hinged together as seen at 24 and one of the halves is also hinged as at 25 to the framing of the car while the other half has a vertical pin 26 capable of traveling in a groove 27 in the door lintel 28 (see Fig. 8).

25 I provide an eye 29 inside the door 3 and a flexible cable 30 which passes over an idle pulley 31 and terminates in a knob or a knot for instance outside partition 7 so as to be readily grasped by the driver when he wishes 30 to close the entrance doors. When on the contrary he desires to open them he pulls on another cable 32 that passes over pulleys 33, 34, and 35 and whose other end is fastened to the door 3 away from the hinge 25, and the 35 two doors are thus folded book wise till they lie flat against each other and against the partition. The position of the doors during opening or closing is shown by the full lines in Fig. 8, and their fully folded (open) position by the dotted lines.

40 If desired cleats or hooks (not shown) may be attached adjacent to the driver at any convenient place for use in retaining the ends of the cables 30, 32.

45 Referring now to what is termed the top deck of the car this is covered as at present but I dispense with the doors and close the upper portion of the ends partly by means of wood paneling 36 and partly by glass and I utilize the center wood panel space for exhibiting the destination of the cars preferably 50 by means of an endless band fixed on rollers 37 and operated by means of bevel gear 38 and handle 39 (see Fig. 4). Furthermore at 55 the top of the stairs I fix boarding or paneling 40 (see Fig. 3) some of the remaining space on the overhanging platform being utilized for a seat 41 fixed to the side and the end of the car. By closing up the ends as beforementioned and providing this seat, I 60 am enabled to seat more passengers than is possible with ordinary cars.

65 As I form the roof with a raised portion 42 in the center it will be necessary in order to prevent passengers coming up the stairs

knocking their heads against the lower portion of the roof, to widen it out just over the top of the stairs, that is, the raised portion expands or dies away to each corner of the car (see Fig. 2) thus providing additional height of roof directly over the stairs and landing to give free head room for passengers.

70 It will be obvious that this car will be a decided improvement on existing double decked ones as passengers entering the car or climbing the stairs will not be obstructed by passengers leaving the car or descending the stairs and as all the passengers leave by the same exit door at the other end of the car and on the same side as the door by which they 75 entered whether they come from the upper deck or not there cannot be any mistake, as the exit door at the guard's end will be closed, while at the same time their onward progress through or over the car is unimpeded.

80 Another important feature is that the stairs leading to the upper deck are under cover.

85 Referring now to Fig. 9 which is a detached section through a portion of the stairs drawn to an enlarged scale, the "risers" or vertical pieces 44 beneath each stair 5 have hitherto been made and located as shown in dotted lines. Now according to my invention I set 90 their bottom edges back, leaning them at an angle as shown in full lines and I thus increase the foothold space of each stair while at the same time still being able to get the same number of treads in the same (or less) 95 space as formerly. This construction combines with the other features of my invention to utilize the available space to great advantage.

100 I claim—

105 1. In a tramcar the combination of a lower deck, an upper deck, stairs located near each end of the car and leading to the latter, entrance doors of double width near each end of the car but at opposite sides thereof and facing said stairs, exit doors of single width located alongside said stairs and at the opposite sides of the car to the entrance doors, and means for closing and opening said doors, whereby the passage of persons through the car is facilitated, substantially as described.

110 2: In a double deck tramcar the combination of stairs connecting the two decks, a roof over the top deck, seats on said deck, a passage way between said seats, a raised portion of said roof over said passage way adapted to give additional head room thereover, and lateral extensions of said raised portion at each end, adapted to give additional head room to passengers using the stairs, substantially as described.

115 3. In a tram-car, panels at each end of the upper deck thereof having open middle spaces providing place for an object such as a route indicator, substantially as described.

120 4. In a tramcar the combination of an exit

door a spindle rigid therewith and forming a portion of a hinge therefor a chain sprocket rigid with said spindle, a chain wheel on a shaft, a chain connecting said chain sprocket and chain wheel, bevel gearing by means of which said shaft may be turned and rack and pinion gearing connected therewith and mov-

able by the motor man, whereby he is enabled to open and close said door at will, substantially as described.

PETER KAVANAGH.
